(57) **CLAIM**

The ornamental design for an industrial gateway module, as shown and described.

DESCRIPTION

FIG. 1 is a top view of an industrial gateway module, showing our new design;
 FIG. 2 is a bottom view thereof;
 FIG. 3 is a rear view thereof;
 FIG. 4 is a front view thereof;
 FIG. 5 is a right side view thereof;
 FIG. 6 is a left side view thereof; and,
 FIG. 7 is a top, front and left side perspective view thereof. The broken lines depict parts of the industrial gateway module that form no part of the claimed design.
